S. WIECHACZY

AEROPLANE

Filed Dec. 9, 1924

Patented July 14, 1925.

1,545,625

UNITED STATES PATENT OFFICE.

STANLY WIECHACZY, OF HAMTRAMCK, MICHIGAN.

AEROPLANE.

Application filed December 9, 1924. Serial No. 754,737.

To all whom it may concern:

Be it known that I, STANLY WIECHACZY, a citizen of Poland, residing at Hamtramck, in the county of Wayne and State of Michigan, have invented certain new and useful improvements in Aeroplanes, of which the following is a specification.

This invention relates to aeroplanes, having more particular reference to an aeroplane provided with movable wings that can be readily adjusted to collapsed position when the aeroplane is not in use, the invention having for an object to provide a novel means for collapsing the wings.

For further comprehension of the invention, and of the objects and advantages thereof, reference will be had to the following description and accompanying drawing, and to the appended claims in which the various novel features of the invention are more particularly set forth.

Fig. 1 of the drawing is a plan view of my improved aeroplane.

Fig. 2 is a transverse sectional view taken on the line 2—2 of Fig. 1.

Fig. 3 is a fragmentary horizontal sectional view taken on the line 3—3 of Fig. 2.

Referring now to the drawing the reference numeral 10 indicates the body of the aeroplane, which may be of the usual elongated shape, and which may be provided with ordinary landing gear, not necessary to be shown here, as the same forms no part of the present invention. The aeroplane is provided with a propeller 11 at its front end, driven by the usual motor, and has the usual directing means 12 at its rear end. A small supplementary motor, for use when landing may also be provided. The aeroplane is supported in flight by a plurality of wings. As here shown front, intermediate and rear pairs of wings, 15, 16 and 17 respectively are shown, although the principle of wing mounting might equally well

be embodied in a single pair of wings. My improved wing mounting that permits of ready collapse of the wings against the body of the aeroplane comprises for each collapsible wing a pair of vertical guides 20 fitted to the side of the body 10 and extending from top to bottom thereof. Each guide supports a block or head 21 that is slidable therein. This block or head is mounted for vertical adjustment by means of a vertical screw 22 that is rotatably mounted at opposite ends in the element 20

and extends through a threaded aperture or boring in the block. The screw 22 is provided with a squared upper end for turning, the screw being held against longitudinal movement.

For supporting the wing when in extended position I provide a pair of lever arms 25 that are fulcrumed between their ends on the longitudinally extending rod 26 mounted in brackets 27 fixed to the side of the body 10. The levers extend obliquely upward and outward from the body when in their normal position, their fulcrum axis being relatively close to their lower ends, these lower ends bearing against the side of the body and being preferably urged against the latter by the springs 28 that are coiled around the rod 26 and connected at opposite ends to said rod and the said lever arms. The lever arms have crosspieces 29 on their upper ends on which the wing rests freely. To retain the wings in position against the upward pressure of the air thereon when the aeroplane is in flight cords or cables 32 are attached to the undersides of the wings and extend inwardly and downwardly, around pulleys 33 mounted on the bottom of the body 10, and upward into the latter through suitable apertures in the bottom thereof, the other ends of these coils being connected to drums 34 mounted on a longitudinally extending shaft 35 in the body 10. This shaft may be supported by means of brackets such as 36 depending from the top of the body 10, and may be provided with suitable means for rotation. As here shown a worm gear 37 is mounted on this shaft and is engaged by a worm pinion 38 on the upper end of a vertical shaft 39 which has a bevel pinion 40 mounted on its lower end. This bevel pinion 40 is engaged by a like pinion 41 on the one end of a short shaft or spindle 42 which has a hand wheel 43 fixed on its other end.

When it is desired to collapse the wings the cables 32 are loosened. The shafts 22 are then rotated to lower the blocks 21, and with them the inner ends of the wings, the wings sliding over the upper ends of the lever supports 25 during this movement. When the blocks reach the lower portions of the guides 20, noses 21' thereon bear on the lower ends of the lever arms 25 and cause the upper ends thereof to be swung inward, these levers finally occupying the position indicated in dotted lines in Fig. 2 of the

drawing. During the inward movement of the upper ends of these levers they bear on the wings and swing the latter to a vertical position alongside of the body of the aero-
5 plane, as will be apparent.

Having thus described my invention, what I claim as new and desire to protect by Letters Patent of the United States is as follows:

- 10 1. In an aeroplane, a body, pairs of vertical guide elements on said body, vertically adjustable blocks on said guide elements, wings hinged to said blocks, means independent of said blocks for supporting the
- 15 said wings against downward swinging movement, and cables connected to said wings to hold the same in extended position against upward pressure of the air thereon.
- 20 2. In an aeroplane, a body, pairs of vertical guide elements on said body, blocks vertically adjustable on said guide elements, wings hinged to said blocks, lever arms fulcrumed between their ends to said body and extending obliquely upward and outward

therefrom to support the said wings against 25 downward swinging movement, and means retaining the said wings against outward swinging movement.

3. In an aeroplane, a body, pairs of vertical guide elements on said body, blocks 30 vertically adjustable on said guide elements, wings hinged to said blocks, lever arms fulcrumed between their ends to said body and extending obliquely upward and outward therefrom to support the said wings against 35 downward swinging movement, and means retaining the said wings against outward swinging movement, the lower ends of said levers projecting into the path of movement of the said blocks to be engaged by 40 the latter to cause the upper ends of said levers to swing the said wings inwardly toward the said body when the lower blocks are adjusted to the lower portions of the said 45 guide elements.

In testimony whereof I have affixed my signature.

STANLY WIECHACZY.
